Primary Examiner — Barbara Fox*Assistant Examiner* — Mehri F Bajoul(74) *Attorney, Agent, or Firm* — Kriegsman & Kriegsman(57) **CLAIM**

The ornamental design for a packaging box, as shown and described.

DESCRIPTION

FIG. 1 is a front perspective view of a packaging box showing our new design;

FIG. 2 is a front view thereof, shown holding a ball in broken line;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a top perspective view of the packaging box of FIG. 1, the packaging box being shown in a partially disassembled state with its ends uncoupled to each other.

The broken line showing of a ball in FIGS. 2–7 depicts environment and forms no part of the claimed design.
